UNITED STATES PATENT OFFICE.

ALFRED SWAN, OF GATESHEAD, COUNTY OF DURHAM, ENGLAND.

ROLL FOR FLATTENING THE ENDS OF TERMINAL WIRES.

SPECIFICATION forming part of Letters Patent No. 276,982, dated May 1, 1883.

Application filed July 20, 1882. (No model.) Patented in England June 19, 1882, No. 2,898.

To all whom it may concern:

Be it known that I, ALFRED SWAN, a subject of the Queen of Great Britain, and residing at Gateshead, in the county of Durham, England, have invented certain improvements in apparatus for flattening out the ends of the terminal wires for incandescent electric lamps preparatory to forming them into tubular or spiral form for the reception of the carbon filament, (for which I have obtained a patent in Great Britain, No. 2,898, dated the 19th day of June, 1882,) of which the following is a specification.

My invention relates to improvements in apparatus for flattening out the ends of the terminal wires of incandescent electric lamps preparatory to forming them into a socket for the reception of the carbon filament. I effect this flattening preferably after the wire has been embedded in the glass of the stem, when, if the said wire terminates in a U form, as in Figure 3, I sever it at the center of the bend, as in Fig. 4, and I straighten out the severed parts and then flatten them out in a press constructed as illustrated in the accompanying drawings, of which—

Fig. 1 is a front view, and Fig. 2 is a transverse section.

The cam-like rollers p p are mounted in a framing, p' , and are geared together by toothed gearing at p^2 , and one of them is provided with a handle, p^3 , for turning the rollers. The opposed pressing-faces of the said cam-rollers p p are cut away, to allow of the introduction to their full extent and thickness of the portions of wire projecting beyond the stem of glass or the like. The said cam-rollers p p , owing to their shape at the parts extending from the point at which they begin to act upon the wire (the position shown

in Fig. 2) to the part at which the flattening takes place, gradually grip upon and gradually flatten out the ends of the wires inserted between them, thus avoiding the weakness resulting from a sudden transition from thick to thin. The main pressing-surfaces of the rolls are concentric with their axes, so that they will flatten the wire equally, leaving the flattened portions of the same width and thickness throughout, except at the junction with the unflattened portion, where there is, as stated, a gradual taper from the flattened to the unflattened portion. The ends of the flattened-out blades (enlarged views of which are shown in Fig. 5) are then cut off, by means of a cutting-press of any convenient form, to an angle, which determines or is determined by the pitch of the spiral to be produced.

Fig. 6 represents a stem with the ends of the terminal wires flattened out and cut, as hereinbefore described.

I claim as my invention—

The described rolls for flattening the terminal wires in incandescent electric lamps, having their pressing-surfaces mainly concentric with the respective axes thereof, but eccentric at the points which act first upon the wire, so as to make a gradual passage from the round to the flat portion, and having also the larger part of one side cut away, substantially as described.

In testimony whereof I have signed my name to this specification in the presence of two subscribing witnesses.

ALFRED SWAN.
